Fig. 2

Fig. 1

Fig. 5

FIGURE 1 is a side elevational view of a fishing reel support and actuator combination, showing my new design;

FIGURE 2 is a top plan view thereof;

FIGURES 3 and 4 are end elevations thereof, taken from the left and right, respectively, of FIGURE 1; and
FIGURE 5 is a bottom plan view thereof.

The fishing reel and fragmentary fishing rod handle shown in broken lines in FIGURE 1 are included for illustration purposes only.

I claim:

The ornamental design for a fishing reel support and actuator combination, as shown and described.
